WITNESS:

Bernard Privat

INVENTOR.
Henry Till
BY
Perry S. Webster
ATTORNEY.

UNITED STATES PATENT OFFICE.

HENRY TILL, OF PITTSBURG, CALIFORNIA.

ADJUSTABLE PARING AND SLICING GAGE FOR KNIVES.

1,236,233.

Specification of Letters Patent.

Patented Aug. 7, 1917.

Application filed May 17, 1917. Serial No. 169,198.

To all whom it may concern:

Be it known that I, HENRY TILL, a citizen of the United States, residing at Pittsburg, in the county of Contra Costa, State of California, have invented certain new and useful Improvements in Adjustable Paring and Slicing Gages for Knives; and I do declare the following to be a full, clear, and exact description of the same, reference being had to the accompanying drawings, and to the characters of reference marked thereon, which form a part of this application.

This invention relates to improvements in knives and is especially designed to provide a means for peeling or slicing fruits, vegetables, breads, meats and any other kind of food to which it is found adaptable.

I am aware that there have been knives made for paring, peeling and slicing but those heretofore in use have been subject to more or less objections, which objections it is the aim of my invention to overcome.

In the first place I provide an attachment which can be affixed to any straight edged knife and can be easily and quickly detached therefrom; it can be reversed so as to be usable by either a right handed or a left handed person; it can be adjusted to provide different depths of cuts so it can be used for both paring and slicing. By having the same detachable it can as noted be placed on any knife and can be readily detached therefrom to permit the knife to be sharpened. By being reversible it permits of the universal use of the same by any person. By being adjustable it can be put to the double use of paring and slicing and also the size of the parings and slices may be varied to suit any desired conditions.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Figure 1 is a perspective view of a knife showing my improved attachment mounted thereon.

Fig. 2 is a front elevation of the complete attachment.

Fig. 3 is an end view of the same as it appears when mounted on the knife blade.

Fig. 4 is a sectional view taken on a line X—X of Fig. 2.

Referring now more particularly to the characters of reference on the drawings the numeral 1 designates the blade of the knife which may be made of any desired type but preferably of that form shown in the drawing. My improved invention embodies first a pair of spring clips 2 adapted to frictionally engage the edge of the knife as shown in Figs. 1 and 3. At points a spaced distance back from the front ends thereof the clips 2 are provided with a pair of vertical posts 3 connected by a top cross bar 4. Depending centrally from the top cross bar 4 is a small plate 5. Screw mounted in this plate 5 is a set screw 6.

The numeral 7 designates a lip provided with a vertical slot 8 mounted over the set screw 6. The lip 7 carries a gage plate 9 which has end sleeves 10 slidable over the posts 3. The said gage plate 9 has an upturned guard 11 along its lower edge. This guard 11 extends just above the front edge of the knife blade 1. By means of the set screw 6 the plate 9 may be set at any desired distance from the knife blade according to whether the knife is to be used for paring or slicing for determining the thicknesses of the parings or slices to be cut.

While the adjustment set forth in the drawings is what I consider the preferable form of the same still in practice there are any number of mechanical means whereby this adjustment may be carried out and I do not wish to be understood to confine myself to the specific form herein set forth.

While I have shown in the drawings a short attachment such as would be used in connection with the peeling and slicing of vegetables, I can provide a longer one for use in slicing bread, meats and the like.

From the foregoing description it will be readily seen that I have produced such a device as substantially fulfills the object of the invention as set forth herein.

While this specification sets forth in detail the present and preferred construction of the device, still in practice such deviations

from such detail may be resorted to as do not form a departure from the spirit of the invention.

Having thus described my invention what 5 I claim as new and useful and desire to secure by Letters Patent is:

1. An attachment for knives comprising a holder consisting of end posts, a top cross bar connecting the posts, a gage plate having sleeves slideable on the posts, and means for fixing the position of the gage plate at 10 desired points.

2. An attachment for knives comprising a holder consisting of end posts, a top cross bar connecting the posts, a gage plate having sleeves slideable on the posts, and means for fixing the position of the gage plate at 15 desired points, such means comprising a depending plate on the cross bar, a set screw

mounted therein, and a lip on the gage plate 20 provided with a slot through which the set screw projects.

3. An attachment for knives comprising a holder consisting of end posts, a top cross bar connecting the posts, a gage plate having sleeves slideable on the posts and an upturned guard on the lower edge of the 25 gage plate.

4. An attachment for knives comprising a holder consisting of end posts, a top cross bar connecting the posts, a gage plate having sleeves slideable on the posts, whereby the space between the gage plate and the knife blade may be varied by sliding the sleeves. 30

35 In testimony whereof I affix my signature.

HENRY TILL.
